UNITED STATES PATENT OFFICE.

WILLIAM H. PALMER, OF ST. LOUIS, MISSOURI.

MEMORIAL ORNAMENT FOR NECKLACES.

SPECIFICATION forming part of Letters Patent No. 365,853, dated July 5, 1887.

Application filed June 21, 1886. Serial No. 205,813. (No model.)

To all whom it may concern:

Be it known that I, WILLIAM H. PALMER, of the city of St. Louis, in the State of Missouri, have invented a certain new and useful 5 Improvement in Memorial Ornaments for Necklaces, &c., of which the following is a full, clear, and exact description, reference being had to the accompanying drawings, forming part of this specification, and in 10 which—

Figure 1 is a perspective view of the necklace with a view of a string and cluster of the memorial frames secured therein. Fig. 2 is an enlarged view of one of the frames with a memorial portrait inclosed and eyelets thereon for the attachments of the coupling-links. Fig. 3 is a vertical section on line 3 3, Fig. 2. Fig. 4 is a back view of the frame with the eyelets transposed to a horizontal position and 20 part broken away to show the interior arrangement of the case. Fig. 5 is a vertical side view of a sleeve-stud with the memorial device attached. Fig. 6 is a vertical section of a locket or watch-charm, showing a double 25 case for holding two memorial pictures. Fig. 7 is a vertical side view of a brooch with the memorial device attached.

My invention relates to a memorial device for a necklace in which mementos of the wearer's friends can be displayed in honor of their memory, and at the same time form an attractive and interesting ornament; and my invention consists in features of novelty, hereinafter fully described, and pointed out in the 35 claim.

Referring to the drawings, in which similar letters of reference indicate like parts, A represents my memorial frame. It is provided with a metal back, B, and front crystal, D, 40 which together inclose a memorial picture, G, (that may be a photograph, tintype, or any other portrait.) The back and crystal are coupled together and incased by a circular concave bead, C, that securely holds the parts 45 of the case together. (See Fig. 1.)

When used in the form of a necklace, (see Fig. 1,) eyelets E are attached at suitable distances around the periphery of the circular bead, and links or rings F, passing through the eyelets of adjacent frames, couple them together. The links may be split rings constructed after the manner of key-rings, or in any other suitable form that will facilitate the attachment and detachment of the memorial frames. H represents a spring snap-clasp for the attachment of the necklace behind. When used in combination with sleeve-studs, (see Fig. 5,) a similar frame to that already described, and which also incloses a memorial picture, has a stem, K, that carries a button-knob, L. When adapted to the form of a brooch, (see Fig. 7,) lugs M', secured to the back disk, have bearings M² for the pivot-pin M which engages, when closed, in a clasp or hook, M³; and, lastly, when constructed in the form of a locket or watch-charm, no back is required, but the case has a double face inclosing two pictures covered by two crystals, which are secured together by the concave clamping-bead before described, (see Fig. 6,) an eyelet, E', being provided whereby to suspend it.

The invention is intended to provide a memorial device that will make an attractive ornament, and at the same time be an interesting memento of the wearer's friends.

I claim as my invention—
In memorial ornaments, the combination of the frames A, having metal backs B and crystals D, coupled together with the circular concave beads C, and inclosing portraits G, the 80 frames arranged to be attached together in the form of a necklace by links F, that engage in eyelets E, secured to the beads, with the snap-clasp H, for fastening the necklace, all substantially as described, and for the purpose 85 set forth.

WILLIAM H. PALMER.
In presence of—
BENJN. A. KNIGHT,
JOE WAHLE.
